Primary Examiner — S. Bryan Reinholdt, Jr.*Assistant Examiner* — Kaitlan N. Oliver(74) *Attorney, Agent, or Firm* — Dinsmore & Shohl LLP(57) **CLAIM**

The ornamental design for a magazine for firearm, as shown and described.

DESCRIPTION

FIG. 1 is a top, front, right perspective view of a magazine for firearm of the present design;

FIG. 2 is a rear, bottom, left perspective view of the design shown in FIG. 1;

FIG. 3 is a front plan view of the design shown in FIG. 1;

FIG. 4 is a rear plan view of the design shown in FIG. 1

FIG. 5 is a left side plan view of the design shown in FIG. 1;

FIG. 6 is a right side plan view of the design shown in FIG. 1;

FIG. 7 is a top view of the design shown in FIG. 1; and,

FIG. 8 is a bottom view of the design shown in FIG. 1.

The broken lines in FIG. 7 depict portions of the magazine for firearm that form no part of the claimed design.
